(57) **CLAIM**

We claim the ornamental design for a battery pack, as shown and described.

DESCRIPTION

FIG. 1 is a rear perspective view of a battery pack in accordance with an embodiment of the present invention. FIG. 2 is another rear perspective view of the battery pack shown in FIG. 1.

FIG. 3 is a top view of the battery pack shown in FIG. 1. FIG. 4 is a bottom view of the battery pack shown in FIG. 1. FIG. 5 is a rear view of the battery pack shown in FIG. 1. FIG. 6 is a front view of the battery pack shown in FIG. 1. FIG. 7 is one side view of the battery pack shown in FIG. 1; and,

FIG. 8 is another side view of the battery pack shown in FIG. 1.

The portions of the battery pack shown in broken lines are included for the purpose of illustrating environment and form no part of the claimed design.
